UNITED STATES PATENT OFFICE.

CHARLES BOLTE, OF JERSEY CITY, NEW JERSEY, ASSIGNOR TO MERSEREAU METAL BED COMPANY, A CORPORATION OF NEW JERSEY.

DESIGN FOR A SPINDLE FOR METAL BED-FRAMES.

46,356.

Specification for Design.

Patented Sept. 8, 1914.

Application filed June 26, 1914. Serial No. 847,541. Term of patent 7 years.

To all whom it may concern:

Be it known that I, CHARLES BOLTE, a citizen of the United States, residing at Jersey City, in the county of Hudson and State of New Jersey, have invented a new, original, and ornamental Design for a Spindle for Metal Bed-Frames, of which the following is a specification, reference being had to the accompanying drawing, forming part thereof.

The figure is an elevation of a spindle for metal bed frames.

I claim:

The ornamental design for a spindle for metal bed frames as shown.

CHARLES BOLTE.
